CLAIM

The ornamental design for an axle for a strapping device, as shown and described.

DESCRIPTION

FIG. 1 is a perspective view of an axle for a strapping device showing my new design;

FIG. 2 is a front elevational view thereof, the opposite end being identical in appearance;

FIG. 3 is a left side elevational view thereof, the right side being a mirror image of that shown;

FIG. 4 is a top plan view thereof;

FIG. 5 is a bottom plan view thereof; and,

FIG. 6 is a perspective view embodying the utilization of my new design, the strapping device depicted by means of broken lines being for illustrative purposes only and forming no part of the claimed design.
